The oven door Fig. 1, is edged with a plain moulding which encloses an ornament consisting of an oval formed boss surrounded by radiating projections of the design illustrated, the whole being surrounded by a waved and foliated ornament.

The lower front plate Fig. 2, has its vertical edges ornamented as shown and has an ornamented upper door A, and two doors with designs similar to those on the oven door Fig. 1.

The upper front plate Fig. 3, has its vertical edges unornamented and has also a design similar to that on the oven door.

The back plate Fig. 4, has its vertical edges ornamented in the same style as the edges of the plate Fig. 2, and has a panel with an ornament differing in form but somewhat similar in character to those on the other plates.

The top plate Fig. 5, is edged on three sides with a plain moulding and in front with the ornamented moulding shown.

The door Fig. 6, is ornamented in a manner precisely similar to that of the doors on plate Fig. 2, the two legs being ornamented in the style shown in Figs. 7 and 8.
